UNITED STATES PATENT OFFICE.

BARTON S. SNOW, OF BATAVIA, ILLINOIS, ASSIGNOR TO T. W. SNOW CONSTRUCTION CO., OF CHICAGO, ILLINOIS, A CORPORATION OF ILLINOIS.

SMOKEJACK.

Application filed April 5, 1923. Serial No. 630,008.

To all whom it may concern:

Be it known that I, BARTON S. Snow, a citizen of the United States, residing at Batavia, in the county of Kane and State of Illinois, have invented a new and useful Improvement in Smokejacks, of which the following is a specification.

My invention relates more particularly to smoke jacks, for use more especially in round-houses, for receiving smoke and gases discharged from locomotive stacks and conveying the smoke and gases to a point exterior of the building in which the locomotives are located.

In accordance with present practice, round-houses are frequently equipped with overhead cranes for transferring from one place to another in the round-house the locomotives as an entirety, or parts thereof, and it is thus desirable that smoke jacks be of such construction that when desired they may be readily manipulated to such positions that they will not be in the way of the cranes referred to, and furthermore be so constructed that they may be manipulated to the desired elevation for cooperation with stacks of different heights and also adjusted at their inlets, to different positions along the track to cause them to extend over the stacks regardless of the various positions at which the locomotives may extend along the track, within certain limits, whereby the stopping of the locomotive at any definite predetermined point is not necessary.

My primary object is to provide a smoke jack which shall be so constructed that the results above referred to may be effected, and to do this by a novel, simple and economical construction which may be readily and positively operated by the attendant.

Referring to the accompanying drawings: Figure 1 is a view in front elevation of a smoke jack constructed in accordance with my invention, the jack being shown as of duplex construction adapting it for cooperation with locomotives located on tracks at opposite sides thereof, one of the movable smoke-conducting conduits of the jack being shown as swung to a position for use and the other thereof in a position paralleling

the track and out of use. Figure 2 is an enlarged view in vertical sectional elevation of a portion of the structure shown in Fig. 1; and Figure 3, an enlarged section taken at the line 3 on Fig. 2 and viewed in the direction of the arrow.

The smoke jack structure shown involves an upright tubular member 4 communicating at its lower end with a conduit 5 located in the floor portion of the building, such as a round-house, in which the jack structure is located, this conduit discharging to any desirable point, preferably outside of the building and in practice being preferably connected with any suitable exhausting mechanism, not shown, for drawing through the conduit 5 the smoke and gases discharged into the smoke jack from the locomotives. The tubular member 4 is provided with oppositely-extending branches 6 which are disposed at substantially a right angle to the two railway tracks (not shown) between which the smoke jack structure is located. The branches 6 open upwardly at the ends thereof as illustrated of the one in Fig. 2, and are each surmounted by a tubular member 7 open at its upper and lower ends and shown as secured in position by screws 8. Telescoped within the upper ends of the members 7 are elbow-shaped pipes 9 affording laterally-extending tubular portions 10 with which latter the pipes 11 are telescoped, the latter being provided at their outer, open ends with depending portions 12 terminating in hollow enlargements 13 at which the jacks extend over the stacks of locomotives to receive the smoke and gases therefrom.

The pipe portions 11 are adapted to be moved in the pipe portions 10 lengthwise of the latter, and the structures comprising the pipes 9 and 11 are adapted to rotate, on a substantially vertical axis, in the upwardly-extending pipes 7, thereby to adapt the structures just referred to to be swung into and out of a position in which they extend crosswise of the tracks.

The upright member 4 is shown as surmounted by a standard 14 on which sheaves 15 are journaled, these sheaves being provided for supporting counterweighting means

for the structures comprising the pipes 9 and 11, these counterweighting means including cables 16 each connected at one end with a respective pipe 9 and provided at its 6 opposite end with a suitable weight 17.

The apparatus shown also comprises means for adjusting the pipes 11 lengthwise of the pipe portions 10, the means shown comprising a substantially horizontally extending screw 18 journaled at an unthreaded collar portion 19 thereof in a wall of the pipe 9 and at the threaded portion 18^a thereof threaded in a spider 11^a secured in the inner end of the pipe 11. The outer end 15 of the screw 18 is equipped with the sheave 18^b which supports an endless chain 18^c extending into a position to be grasped by the attendant and through the medium of which the shaft 18 is rotated in either direction as 20 desired, to move the pipe 11 to different positions of adjustment crosswise of the track.

Means are also provided for raising and lowering the structures formed of the pipes 9 and 11 and rotating them in the respective tube portions 7. The means shown for this purpose comprise, as to each of the smoke-conducting portions at opposite sides of the smoke jack structure, a tube 20 which has bearing toward its lower end in an arm 21 extending laterally from the tubular portion 4 and extends upwardly through an opening 6^a in the adjacent branch pipe, and into the tubular member surmounting the latter in which it is concentrically positioned. The upper end of the side wall of the tube 20 is vertically slotted, as represented at 20^a, and through this slot extends a radial web 23 which is connected at its outer end with a ring 24 secured to the lower end 35 of the pipe 9 the web being connected at its inner end with a head 25 located within the tube 20 and having sliding fit therein, this head containing a vertically-extending threaded bore 26. The lower end of the tube 20 is provided with a collar 27 rigidly secured thereon which latter bears against the upper surface of the supporting arm 21, the tube 20 being also provided with a handle 28 rigid thereon and through the medium of which the tube 20 may be rotated. The means referred to also comprises a shaft 29 extending lengthwise through the tube 20, the upper end of this shaft being threaded, as represented at 30, and screwing into the 45 threaded bore 26 of the head 25, the upper extremity of the shaft 29 being provided with a nut 31 screwing down upon a disk 32 surrounding the shaft 29 and bearing against the upper end of the tube 20. The lower end of the shaft 29 is equipped with a hand wheel 33 through the medium of which this shaft is rotated. It will be understood 50 from the foregoing that by reason of the location of the web 23 in the slot 20^a, rotation of the tube 20, through the medium of the

handle 28, will cause the pipe portion 9 to be swung about a vertical axis, and that by reason of the engagement of the shaft 29 with the head 25, the shaft 29 being held against vertical movement, rotation of the latter, through the medium of the hand wheel 33, will cause the head 25, and consequently the structure comprising the pipes 9 and 11, to be raised or lowered, depending on the direction of rotation of the shaft 29, 75 it being noted that in the position occupied by the various parts in Fig. 2, the pipe structure referred to is adjusted to its highest position.

From the foregoing description it will be noted that the laterally-projecting pipe portions of the smoke jack may be readily swung into and out of a position in which they extend crosswise of the track, as, for example, to the position shown of the pipe structure 85 at the left hand side of Fig. 1, in which position they may parallel the track and thus be entirely out of the way of cranes in their operation between the engines and the roof of the building. Furthermore it will be noted 90 the inlet ends of the jacks may be adjusted to various elevations to adapt these smoke inlets to be adjusted, with the desired degree of accuracy, to the locomotive stacks and also that the outer telescoped portions of the pipe structures may be adjusted toward and away from the supporting structure of the jack, this feature, in combination with the adaptability of the pipe portions of the jack 95 to rotation about vertical axes, permitting 100 of the accurate adjustment of the inlets of the jack relative to the stacks irrespective of the particular point at which the locomotives may be stopped relative to the jacks, 105 within certain ranges.

While I have illustrated and described a particular construction embodying my invention, I do not wish to be understood as intending to limit it thereto as the same may be variously modified and altered without departing from the spirit of the invention.

What I claim as new, and desire to secure by Letters Patent, is:

1. A smoke jack comprising a base containing a smoke passage, and a laterally-extending tubular portion forming a smoke conduit adapted at its outer end to receive the discharge from the locomotive stack positioned adjacent thereto, said tubular portion being supported on said base and communicating with the smoke passage therein and constructed and arranged to be swung on said base into different angular positions in a plane at an angle to the vertical.

2. A smoke jack comprising a base containing a smoke passage, and a laterally-extending tubular portion forming a smoke conduit adapted at its outer end to receive the discharge from the locomotive stack

- positioned adjacent thereto, said tubular portion being supported on said base and communicating with the smoke passage therein and constructed and arranged to be swung on said base into and out of a position in which it extends substantially at right angles to the position it assumes when receiving the discharge from a locomotive stack.
3. A smoke jack comprising a base containing a smoke passage, and a laterally-extending tubular portion forming a smoke conduit adapted at its outer end to receive the discharge from the locomotive stack positioned adjacent thereto, said tubular portion being supported on said base and communicating with the smoke passage therein and constructed and arranged to be swung on said base, in a plane at an angle to the vertical and movable up and down to adapt its inlet end to extend at different elevations.
4. A smoke jack comprising a structure containing a smoke passage, and a laterally-extending tubular portion forming a smoke conduit adapted at its outer end to receive the discharge from a locomotive stack positioned adjacent thereto, said tubular portion opening into said smoke passage and being bodily movable relative to said structure to position its inlet at different elevations and rotatable into different angular positions in a plane at an angle to the vertical.
5. A smoke jack comprising a base containing an upwardly-extending smoke passage, and a laterally-extending tubular portion forming a smoke conduit adapted at its outer end to receive the discharge from a locomotive stack positioned adjacent thereto, said tubular portion being supported on said base and opening into said smoke passage and bodily movable up and down on said base to position its inlet at different elevations and rotatable on said base into different angular positions in a plane at an angle to the vertical.
6. A smoke jack comprising a base containing a smoke passage, and a laterally-extending tubular portion forming a smoke conduit adapted at its outer end to receive the discharge from a locomotive stack positioned adjacent thereto, said tubular portion being supported on said base and communicating with the smoke passage therein and constructed and arranged to be swung on said base into different angular positions in a plane at an angle to the vertical and its inlet portion being adjustable toward and away from said base.
7. A smoke jack comprising an upwardly-extending smoke conduit having a laterally-extending tubular portion, a tubular member telescoping therewith and containing an inlet for the smoke and gases, and mechanism for moving said tubular member lengthwise in said laterally-projecting portion.
8. A smoke jack comprising an upwardly-extending conduit, a pipe telescoping with said conduit and provided with a laterally-extending tubular portion containing an inlet for the smoke and gases, and mechanism for rotating said pipe relative to the part with which it is telescoped.
9. A smoke jack comprising an upwardly-extending conduit, a pipe telescoping with said conduit and provided with a laterally-extending tubular portion containing an inlet for the smoke and gases, and mechanism for raising and lowering said pipe relative to the part with which it is telescoped.
10. A smoke jack comprising an upwardly-extending conduit, a pipe telescoping with said conduit and provided with a laterally-extending tubular portion containing an inlet for the smoke and gases, mechanism for rotating said pipe relative to the part with which it is telescoped, and mechanism for raising and lowering said pipe relative to the part with which it is telescoped.
11. A smoke jack comprising an upwardly-extending tubular portion, a pipe telescoping with said tubular portion and provided with a laterally-projecting portion containing an inlet for the smoke and gases, a nut carried by said pipe and connected with the latter through the medium of a web, a suitably-supported rotatable tube extending upwardly into said tubular portion and containing a slot in its side wall through which said web extends, said nut being located within said tube, and an actuating, threaded, shaft extending in said tube and having threaded engagement with said nut, for the purpose set forth.
12. A smoke jack comprising an upwardly-extending smoke conduit, and a pipe telescoping with said conduit to adapt said pipe to be raised and lowered and having a laterally-extending portion adapted at its outer end to receive the discharge from a locomotive positioned adjacent thereto.
13. A smoke jack comprising a base containing a smoke passage, and a laterally-extending tubular portion forming a smoke conduit adapted at its outer end to receive the discharge from a locomotive stack positioned adjacent thereto, said tubular portion being formed of lengthwise adjustable sections and supported on said base and communicating with the smoke passage therein and constructed and arranged to be swung on said base into different angular positions in a plane at an angle to the vertical.
14. A smoke jack comprising an upwardly-extending smoke conduit, and a pipe

telescoping with said conduit to adapt said pipe to be raised and lowered, said pipe having a laterally-extending portion formed of lengthwise adjustable sections and 5 adapted at its outer section to receive the discharge from a locomotive stack positioned adjacent thereto.

15. In combination, a railway track, a smoke pipe located adjacent the ground, 10 and a pipe rising from said smoke pipe and having a laterally-extending tubular portion forming a smoke conduit adapted at its outer end to receive the discharge from a locomotive stack positioned adjacent thereto, said tubular portion being adapted 15 to be swung into different angular positions in a plane at an angle to the vertical.

16. In combination, a railway track, a smoke pipe located adjacent the ground, 20 and a pipe rising from said smoke pipe and having a laterally-extending tubular portion forming a smoke conduit adapted at its outer end to receive the discharge from a locomotive stack positioned adjacent thereto, said tubular portion being adapted 25 to be swung in a plane at an angle to the vertical and movable up and down to adapt its inlet end to extend at different elevations.

17. In combination, a railway track, a smoke pipe located adjacent the ground, 30 and a pipe rising from said smoke pipe and having a laterally-extending tubular portion forming a smoke conduit adapted at its outer end to receive the discharge from 35 a locomotive stack positioned adjacent thereto, said tubular portion being bodily movable relative to the structure to position its inlet at different elevations.

18. In combination, a railway track, a smoke pipe located adjacent the ground, 40 and a pipe rising from said smoke pipe and having a laterally-extending tubular portion forming a smoke conduit adapted at its outer end to receive the discharge from a locomotive stack positioned adjacent thereto, said tubular portion being bodily movable relative to said structure to position its inlet at different elevations and rotatable into different angular positions in 45 a plane at an angle to the vertical. 50

19. In combination, a railway track, a smoke pipe, and a pipe communicating with said smoke pipe at one side of said track and having a laterally-extending portion forming a smoke conduit adapted at its outer end to receive the discharge from a locomotive stack positioned adjacent thereto, said tubular portion communicating with 55 said smoke pipe and being constructed and arranged to be swung into and out of a position in which it extends crosswise of the track.

20. In combination, a railway track, a smoke pipe located adjacent the ground, 60 and a pipe communicating with said smoke pipe at one side of said track and having a laterally-extending portion forming a smoke conduit adapted at its outer end to receive the discharge from a locomotive stack positioned adjacent thereto, said tubular portion communicating with 65 said smoke pipe and being constructed and arranged to be swung into and out of a position in which it extends crosswise of the track. 70

BARTON S. SNOW.
